HOUSING FOR A FIBER OPTIC LIGHT SOURCE

Frank L. Rose, Andover, Mass., assignor to Avco Corporation, Cincinnati, Ohio, a corporation of Delaware

Filed Oct. 2, 1963, Ser. No. 76,828

Term of patent 14 years

(Cl. D26—5)

The figure is a perspective view of a housing for a fiber optic light source, showing the top, front, and one side of my new design.

The side not shown is substantially similar to the side shown, while the bottom and rear of the housing are flat and unornamented.

The broken line showings of a top handle, side vent, and frontal controls are for illustrative purposes only.

The characteristic feature of my design resides in the combination, and a housing of the shape disclosed, of the circular, screened top opening in conjunction with a centrally located frontal cylindrical protuberance embodying a transverse latch mechanism for securing the fiber optic light cable, all as shown.

I claim:

The ornamental design for a housing for a fiber optic light source, as shown and described.
